Primary Examiner — Jae Liang(74) *Attorney, Agent, or Firm* — Chun-Ming Shih;
LanWay IPR Services(57) **CLAIM**

The ornamental design for a spout of travel mug, as shown and described.

DESCRIPTION

FIG. 1 is a perspective view of a spout of travel mug showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an environmental perspective view thereof.

The broken lines in the drawings depict environmental subject matter and portions of the spout of travel mug that form no part of the claimed design.

1 Claim, 5 Drawing Sheets(56)
